Primary Examiner — John Windmuller*Assistant Examiner* — Steven Czyz(74) *Attorney, Agent, or Firm* — Hamre, Schumann,
Mueller & Larson, P.C.**CLAIM**

I claim the ornamental design for an oval knitting loom, as shown and described.

DESCRIPTION

FIG. 1 is a perspective view of an oval knitting loom, shown with a pair of legs deployed from the oval frame;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the oval knitting loom, shown with the pair of legs folded onto the oval frame;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a cross-sectional view thereof, taken along line 15-15 in FIG. 13.
